Application October 20, 1932, Serial No. 638,716

4 Claims. (Cl. 154—37)

This invention relates to an improved apparatus for making artificial leather or like material, and the main objects of the invention are to provide a practical and economical apparatus for the continuous production of a uniform artificial leather or like product; to provide means for impregnating a web of absorbent paper or other material with latex or other binding material and to compress such impregnated web to a definite thickness; to provide means for controlling the proportion of binding material in the product; to provide means for insuring thorough impregnation of the web with the desired proportion of binding material; to provide an arrangement for handling and compressing the wet web without material danger of breaking the web while subjecting the same to compression; and in general, it is the object of the invention to provide an improved apparatus for making a product of the kind referred to.

Other objects and advantages of the invention will be understood by reference to the following specification and accompanying drawings (5 sheets) in which is illustrated an improved apparatus for accomplishing the above stated objects in producing an artificial leather or like product.

In the drawings:—

Fig. 1 is a side elevation.

Fig. 2 is a section on the line 2—2 of Fig. 1.

Fig. 3 is a side elevation on an enlarged scale of a lower portion of the mechanism shown in Fig. 1, certain parts being shown in section to more clearly illustrate the details of the construction.

Fig. 4 is a fragmentary sectional view of the upper portion of the mechanism shown in Fig. 1.

Fig. 5 is a section on the line 5—5 of Fig. 4.

Fig. 6 is a fragmentary plan view of a portion of the mechanism at the top of Fig. 1.

Fig. 7 is a detail sectional view illustrating a cleaning device.

Fig. 8 is a diagrammatic representation of a modified form of mechanism.

Referring now to the drawings, and more particularly to Fig. 1, a plurality of sheets of creped paper are indicated at 10, six such sheets being indicated in this instance, although the number of sheets may be varied to suit particular requirements of the product to be made. It will therefore be understood that the six sheets illustrated represent any number of sheets, one or more, which are to be treated according to the process of the machine about to be described. The sheets are fed into the bite of a pair of cooperatively arranged guide rollers 11—11, from which the

single sheet or multi-ply sheet designated 12 passes downwardly into the mechanism about to be described. The sheets 10 may be either single or multi-ply sheets and they are drawn from any suitable source of supply not herein illustrated. 5

This machine embodies a plurality of pairs of cooperatively arranged compression rolls 13—13, there being illustrated in this instance six pairs of such rolls arranged in vertically spaced and aligned relationship. One of the rolls 13, in this 10 instance the right hand one in Fig. 1 of each pair of rolls is rotatably mounted in a fixed bearing carried by frame members such as 14. The other roll 13 of each pair is rotatably mounted in a bearing 15 which is slidably adjustably mounted 15 on a bracket such as 16 carried by a cross member such as 14.

For adjusting the adjustable roll 13 towards and from its cooperating, stationary roll 13, the bearing 15 at each end of the roll is connected by 20 means of a shaft 17 to a device 18 which includes a rotatably mounted worm wheel having an axial aperture threaded to receive the threaded end 19 (Fig. 2) of the shaft 17. Cooperating with the said worm wheel, there is a worm gear rotatably mounted and carried by a shaft 20 which is provided at one end with a hand wheel 21 whereby the shaft and worm gears may be rotated to effect rotation of the worm wheels to thereby longitudinally adjust the shaft 17 and 30 the adjustable roll 13. Inasmuch as worm and worm wheel devices such as 18 are well-known, it is considered unnecessary to illustrate the same in detail.

The supporting brackets 14—14 are supported 35 by standards 22—22, and other frame work indicated at 23 is suitably connected with the said standards so as to form supporting means for additional elements which will presently be referred to.

A pair of belts 24—24 of foraminated material; for example, woven wire of about 90 mesh, are respectively associated with one roller of each pair so that adjacent active reaches of the belts 24 are pressed towards each other between the 45 successive pairs of rolls 13 and inactive portions of each belt are guided through cleaning boxes 25—25, around adjustable belt tensioning rollers 26, around stationary guide rollers 27 and over adjustable guide rollers 28. 50

The tension of the belts 24, as above indicated is controlled by the tension adjusting rollers 26, these rollers being carried by brackets 29 which are mounted for adjustment along screw threaded shafts such as 30 which are rotatable through the 55

agency of hand wheels such as 31, the latter being suitably geared to the said screw threaded shafts. A guide member 32 acts on the lower end of the bearing bracket so as to prevent rotation of the bracket about the shaft 30. An auxiliary tensioning effect is obtained by adjusting the guide rollers 28, these rollers being carried by bearing blocks 33 which are adjustable along screw threaded shafts such as 34 which are rotatable 10 through the agency of hand wheels 35.

The chief function of the belts 24 is to effect the thorough impregnation and permeation of the web by the binding liquid, which it does by its kneading action on the web.

15 Above the stack of compressing or calendering rolls 13, there is formed a supporting frame work 36 on which are mounted a pair of head boxes 37 (Fig. 6) into which a suitable binding fluid or compound; for example, latex or a latex compound, is fed from weir or meter boxes 38 into which such material is fed through the agency of pipe lines 39 connected to a suitable source of supply. Valves as indicated at 40 are provided in the pipe line for shutting off the supply of material when desired.

30 The head boxes 37 are illustrated in greater detail in Figs. 4, 5, and 6, to which attention is directed. Each head box consists of a generally rectangular receptacle having its front wall provided with a pair of longitudinally adjustable gates 41—41 which are slidably mounted in the front wall in any suitable manner; for example, by means of tongues and grooves as illustrated in Fig. 4. By adjusting the gates outwardly, an 35 opening 42 is provided centrally of the length of the head box and the binding material indicated at 43 in Fig. 4 may then flow by gravity through the opening 42, down an apron 44 and into the nip or trough formed by the adjacent upper surface 40 portions of the uppermost pair of rolls 13. The gate members 41—41 are adjustable through the agency of a shaft 45 having right and left hand screw threading at its opposite ends respectively for engaging corresponding internally threaded 45 brackets 46 which are secured to the respective gates 41. The shaft 45 is rotatably supported by suitable brackets such as 47 and a hand wheel 48 is provided at one end of the shaft for facilitating rotation of the shaft.

50 The operation of the mechanism in producing a product such as artificial leather may now be described as follows: The webs of material 10 are brought together between rolls 11 so as to form, in effect, a single or multi-ply web 12 which, 55 moving downwardly enters the bite between the foraminous belts 24 carried by the respective vertically aligned rolls 13 of each pair of rolls. Before entering the bite of the said foraminous belts 24, the web 12 passes through the bath of binding 60 material in the trough formed between the uppermost pair of rollers 13, and hence becomes thoroughly soaked or impregnated with the binding material. Of course, a quantity of the material "piles up" in the center of the trough, but 65 its depth gradually lessens towards the ends of the trough, and hence end guides for retaining the material in the trough are not required. Piling up of the binding material and omission of end guides is made possible because of the consistency of the binding material, because of the 70 central delivery of the binding material, and because of the effective control afforded by the gates 41—41 of the flow of binding material to the trough, which permits the said flow of material 75 to be regulated to supply the material at ap-

proximately the same rate as it is absorbed by the web.

In its passage between the belts 24 and between the successive pairs of rollers 13, the web 12 is subjected to successively increased compression 5 so that the binding material is effectively worked through the web and excess binding material is squeezed therefrom. It will be understood that a gradually increased compression of the web is effected by correspondingly adjusting the pairs of 10 rolls 13. The web of material issues from beneath the lowermost pairs of rolls 13 and is deposited on a conveyor 49 which carries the web to a suitable drying kiln, not illustrated. The product thus formed is a tough, flexible sheet of material 15 having a certain amount of resiliency and elasticity. It has been found suitable for use in many ways as a substitute for leather, and hence, for convenience may be designated artificial leather. The fine mesh wire belt between which the product is compressed impresses upon the surface of 20 the product a sort of fine woven appearance which is quite desirable and pleasing to the eye.

As an incident to the compression of the web between the successive pairs of rolls 13, a certain 25 amount of the binding fluid is pressed out of the web and adheres to the surfaces of the said rolls. For removing such material from the surfaces of said rolls, doctor blades 50 such as illustrated best in Fig. 4 are provided. As shown in Fig. 4, 30 the doctor blades 50 are mounted on pivoted brackets 51 which are provided with outwardly extending arms 52 having weights 53 on their free ends whereby the doctor blades 50 are yieldingly maintained in engagement with the surfaces 35 of the respective rolls 13. The blades 50 are effective to scrape from the roll surfaces the binder adhering thereto. The material thus scraped from the roll surfaces is caught in a pan or the like 54 which is carried by the bracket 51 and 40 the said pan is provided with a drain outlet 55 through which the binding fluid may empty into a trough 56 which leads into a drain pipe 57. Each of the rolls 13, except the lowermost pair 45 of rolls, is provided with a doctor blade arrangement such as just described so that they are all maintained clean.

Because of space limitations in the mechanism, a special arrangement of doctor blades is provided for the lowermost pair of rolls, this arrangement being clearly shown in Fig. 3. By reference to Fig. 3, it will be seen that doctor blades such as 58 are associated with the upper surface portions of the rolls, such blades being carried by pivotally mounted brackets 59. Weighted arms 55 60 connected to the said brackets 59 serve to yieldingly maintain the doctor blades 58 in operative engagement with the surfaces of the rolls so as to scrape the adhering binding material therefrom. The amount of material thus scraped from the lowermost rolls 13 is very small, if not negligible, these doctor blades being provided more as a precautionary measure rather than as a matter of necessity. The material removed by the doctor blades 58 runs to one side and is permitted 65 to drip into a drip pan 61 which is suitably positioned and supported below the lowermost pair of rolls 13.

The wire belts 24—24 also carry off a certain amount of the binding material, and for removing the same from the belts, the cleaning boxes 25 are provided. As clearly shown in Figs. 1 and 3, the wire belts are guided in an upward direction from the lowermost rolls 13 and enter the boxes 25 through slots such as 62, pass over roll- 75

ers such as 63 under rollers such as 64, thence upwardly and over tension adjusting rollers 26. Intermediate the guide rollers 63 and 64 in the cleaning boxes, the belts are subjected to sprays or showers of cleaning fluid or liquid delivered by a series of shower pipes such as 65. Water may conveniently be used for this purpose. Intermediate the shower pipes 65, there are provided rotating beaters or cleaning brushes 66 which are 10 constructed substantially as shown in Fig. 7.

Each brush includes a shaft 67 which carries a pair of disks 68 in spaced relation. A series of bars 69 of wood or other material are secured in circumferentially spaced relation to the spaced disks 68, and these bars carry beaters formed of a strip 70 of felt or the like which is folded upon itself and has interposed between its folds a rubber strip 71. The beater element thus formed is secured to the bar 69 by suitable clamping means 20 such as indicated at 72.

Each of the rolls 13 is positively driven at the same surface speed so that the belts 24—24 are also driven by reason of their frictional contact with said rollers. The means for driving the rolls 25 13 includes a speed reducing driving mechanism 73 (Fig. 3) which may be of any conventional construction, the power source for the speed reducer being here indicated as a pulley 74 which is driven by a belt 75 which in turn is driven from 30 any suitable source of power. The speed reducer delivers its driving power through a gear 76 which meshes with a gear 77 secured to one end of the shaft of the stationary roll of the lowermost pair of rolls 13. At its other end, the shaft of said lowermost roll is provided with a gear 78 which meshes with a pinion 79 fixedly mounted for rotation on the bracket 14. The corresponding end of the shaft of the cooperating roll 13 is provided with a gear 80 which meshes with a pinion 81, 40 the latter also meshing with the pinion gear 79.

In order to permit one of the rollers 13 to be adjusted towards and from the other roller 13, without impairing the driving connection between the rolls, the gear 81 is rotatably mounted on a 45 stud 82 that forms a pivotal connection between arms 83 and 84, the free ends of which arms are respectively pivoted on the shaft of the roller 13 and the pivot shaft of the gear 79. It will be seen that when the rolls 13 are adjusted toward 50 or away from each other, the links or arms 83 and 84 will effectively maintain the floating pinion gear 81 in mesh with both gears 79 and 80.

Each pair of rolls 13 is provided with a gear connection such as 78, 79, 80, and 81, and for 55 transmitting driving power from one pair of rolls to the next higher pair of rolls, gears such as 85 each driven by a sprocket and chain connection from the shaft of the underlying roll 13 are rotatably mounted on the standard 22 for transmitting rotation from the gear 77 of one pair of 60 rolls to the gear 77 of the next higher pair of rolls.

For effecting rotation of the beater brushes 66 of the belt cleaning boxes, the shaft of the next 65 to the lowermost stationary roll 13 is provided with a pair of sprockets as indicated in Fig. 2 for receiving chains 86 and 87 which respectively engage sprockets carried by extended ends of the shafts of one beater brush in each box. The various beater brushes in each box are interconnected for rotation by means of gear trains such 70 as indicated at 88.

In Fig. 8, a modified arrangement of the structure is illustrated and in this arrangement, the 75 foraminous belts 24 are guided between an up-

permost pair of rollers 89 and between two pairs of lower rollers 90 and 91 respectively. Intermediate the pairs of rollers 89 and 90, there are three rollers 92, 93, and 94 around which the wire belts 24 are threaded so as to follow a zigzag 5 path of travel substantially as illustrated. By maintaining the belts taut, the desired compressive effect on the web between the belts may be obtained by this arrangement as well as by the previously described arrangement which involves 10 an increased number of roll pairs.

We claim as our invention:—

1. Apparatus for making artificial leather and the like, comprising, in combination a frame, a vertically disposed group of pairs of press rolls 15 journaled on said frame, independent means associated with each pair for varying the pressure between them, a pair of head boxes for a binding liquid mounted above the topmost pair of rolls, adjustable gates in the inner opposed walls of 20 said head boxes controlling the size of the flow openings from said boxes, aprons for conducting the liquid from said openings to the nip of the topmost rolls, a pair of guide rollers above said head boxes into the nip of which a plurality of 25 plies of creped paper are received and compacted and by which the resultant web is directed into the nip of said topmost pair of press rolls, and means for driving said pairs of press rolls in the same direction at equal speeds whereby to advance said web between them.

2. Apparatus for making artificial leather and the like, comprising, in combination a frame, a vertically disposed group of pairs of press rolls journaled in said frame, a pair of oppositely disposed reticulated endless belts extending between and in contact with the rolls of the several pairs, means associated with each pair of rolls for bodily adjusting one roll toward and from its companion roll whereby to vary the pressure between 40 them, a pair of head boxes for a binding liquid mounted above the topmost pair of rolls, adjustable gates in the inner opposed walls of said head boxes controlling the size of the flow openings from said boxes, aprons for conducting the liquid 45 from said openings to the nip of the topmost rolls, a pair of guide rollers above said head boxes into the nip of which a plurality of plies of creped paper are received and compacted and by which the resultant web is directed between said belts 50 at the nip of the topmost pair of press rolls, means for driving said pairs of press rolls in the same direction at equal speeds whereby to advance said belts and web between them, and a discharge conveyor underlying the lowermost of 55 said pairs of press rolls.

3. Apparatus for making artificial leather and the like, comprising, in combination a frame, a vertically disposed group of pairs of press rolls journaled in said frame, a pair of oppositely disposed woven wire endless belts extending between and in contact with the rolls of the several pairs, guiding and tensioning means for the inactive portions of said belts, means for cleaning said belts operating on said inactive portions, means 65 associated with each pair of rolls for bodily adjusting one roll toward and from its companion roll whereby to vary the pressure between them, a pair of oppositely disposed head boxes for a binding liquid mounted above the topmost pair 70 of rolls, adjustable gates in the inner walls of said head boxes controlling the width of the flow openings from said boxes, aprons for conducting the liquid from said openings to the nip of the topmost rolls, a pair of guide rollers located cen- 75

- trally above said head boxes into the nip of which a plurality of plies of creped paper are received and compacted and by which the resultant web is directed between said belts at the nip of the 5 topmost pair of press rolls, means for driving said pairs of press rolls in the same direction at equal speeds whereby to advance said belts and web between them, and a discharge conveyor underlying the lowermost of said pairs of press rolls.
- 10 4. In a machine of the class described, the combination of a pair of compressing rolls, means for mounting said rolls for adjustment towards and from each other, means for driving said rolls at uniform speed including pairs of gears respec-

tively secured to said rolls, a pair of pinion gears respectively meshing with said pair of gears and with each other, one of said pinion gears being mounted in axially fixed relation to the roll gear with which it meshes, and means for mounting 5 the other of said pinion gears for peripheral adjustment relative to the roll gear with which it meshes and to the fixed pinion gear, thereby to maintain said gears in predetermined operative relationship throughout all adjusted positions of 10 the compression rolls.

JOHN B. CATLIN.
